GAME APPARATUS

Frank K. Maitland, Hermosa Beach, Calif., assignor to Fred C. McClellan, Chicago, Ill.

Application March 14, 1935, Serial No. 11,084

6 Claims. (Cl. 273—121)

This invention relates to a game apparatus. It is an object of this invention to provide an improved game apparatus, which is relatively simple and inexpensive in construction and efficient 5 in use.

Another object of the invention is to provide, in a game apparatus, the combination of: a cabinet including an inclined playing board provided with a ball seat and having an annular 10 row of ball exit openings therein circumferentially arranged relative to said ball seat; and means including a device actuated by a ball entering upon said ball seat for successively moving balls from said ball seat into said exit openings.

Other objects will appear hereinafter.

The invention consists in the novel combination and arrangement of parts to be hereinafter described and claimed.

20 The invention will be best understood by reference to the accompany drawings, showing the preferred form of construction and in which:

Fig. 1 is a fragmentary top plan view of a game apparatus embodying a preferred form of the 25 present invention;

Fig. 2 is a vertical sectional view on line 2—2 in Fig. 1;

Fig. 3 is a top plan view, on line 3—3 in Fig. 2, of certain parts of the operating mechanism 30 embodied in the new game apparatus;

Fig. 4 is a diagrammatic view of an electromagnetic circuit embodied in the invention;

Fig. 5 is a diagrammatic view of another electromagnetic circuit embodied in the new apparatus; and

Fig. 6 is a sectional detail view on line 6—6 in Fig. 2.

A game apparatus embodying a preferred form 40 of the present invention is shown in the drawings, is therein generally indicated at 10, and comprises a cabinet 11 which includes an inclined playing board 12.

The inclined playing board 11 is provided with 45 an annular row of ball exit openings 13 (Figs. 1 and 2), and arranged upon the inclined playing board 12 around the row of ball exit openings 13 is a guide rail 52 (Figs. 1 and 2). Arranged in the cabinet 11 below the inclined playing board 12 is a slidable panel or ball-retaining member 14 (Fig. 2). Mounted upon the inclined playing board 12, within a slot 53 which is formed in slidable panel 14, are a pair of normally spaced electrical contacts 15—16. These contacts 15—16 55 are embodied in an electromagnetic circuit 17

(Fig. 5), which also includes a solenoid 18, this solenoid 18 being mounted in a cabinet 11 upon the bottom wall 52 thereof.

Mounted above, and adapted to be attracted by, the solenoid 18 is a pivotal member 19, this member 19 being pivotally mounted between its ends, as at 20, upon a support 21 and being normally urged in a counterclockwise direction (Fig. 2) by a spring 22.

Carried by the pivotal member 19 is a latch 23, the upper end portion 24 of this latch arm 23 being adapted to latchingly engage in an opening 25 which is formed in a pulley or sheave 26 which is rotatably mounted in the cabinet 11 upon an upright bearing post 27, the bearing post 27 being mounted on the bottom floor 52 of the cabinet 11 (Fig. 2).

Working around the pulley or sheave 26 is an endless power transmitting element or belt 28 and this belt 28 also works around a smaller 20 pulley or sheave 29 which is mounted upon a vertical shaft 30, the vertical shaft 30 being mounted in the cabinet 11 upon the bottom floor 52 thereof (Fig. 2).

Carried by the vertical shaft 30 is a ratchet 31 (Figs. 2 and 6) and engageable with this ratchet 31 is a pawl 32. This pawl 32 is pivotally mounted adjacent the ratchet 31 and has an arm 49 which is provided with a slot 48 and projecting upwardly into this slot 48 is the upper end portion 50 of a vibratory member 51. This member 51 is adapted to be vibrated by an electromagnetic device 33, which is of the make and break type, and is of conventional design.

The pulley 26 has an upwardly extending flange or rib 35 and engageable with this flange 35 is a laterally extending arm 36 of a vertical rod or shaft 37, this shaft 37 extending upwardly through the cabinet 11 through an opening in the ball return runway 46, and through an opening 38 provided in the sliding panel 14. At its upper end this shaft 37 carries a dial hand or indicator 39 and this dial hand or indicator 39 has a bifurcated end portion which provides a pair of spaced arms 40; these arms 40 being arranged above the playing surface 12 and above the plane of the main extent of the indicator 39 (Fig. 2).

Arranged upon the inclined playing board 12 is a ball runway 41 by means of which played balls may be guided, one at a time, onto a ball seat 42 which is adapted to move the contacts 15 and 16 into engagement with each other when a ball is disposed thereon. For this purpose the 50 55 55

ball seat 42 carries a depending pin 47 (Fig. 5) which is adapted to engage the contact 15.

Operation

5 When a played ball, propelled onto the upper portion of the inclined playing board 12, (by conventional means not shown) enters the runway 41 it will travel down the latter and enter onto the ball seat or disc 42, whereupon its weight 10 will cause the pin 47 carried thereby to engage the contact 15 with the contact 16 and thereby close the electromagnetic circuit 17 (Fig. 5). This closing of the circuit 17 causes the solenoid 18 embodied therein to attract the pivotal latch 15 member 19-23, thereby moving the upper end portion 24 of the latch member 23 out of the opening 25 in the pulley 26 and thus moving the same out of latching engagement with the pulley 26. At the same time, this movement of the latch 20 member 23 causes the lower end thereof to engage the contact 48, (Fig. 2), thereby closing the electromagnetic circuit 34 (Fig. 4). This closing of the circuit 34 causes the solenoid 33 embodied therein to vibrate the make and break 25 member 51-53, thereby alternately moving the pawl 32 into and out of engagement with the ratchet 31, thereby rotating the ratchet 31 (in a clockwise direction, Fig. 6). This movement of the ratchet 31 acts, through the shaft 30, to 30 rotate the pulley 29 and the motion of the pulley 29 is transmitted, by way of the belt 28, to the pulley 26, thereby rotating the pulley 26 (clockwise, Fig. 3). This movement of the pulley 26 causes the upstanding flange 35 thereon 35 to engage the arm 36 of the shaft 37, thereby rotating the shaft 36-37 (clockwise, Fig. 3). This movement of the shaft 36-37 acts upon the indicator hand 39 and its arms 40 to turn the latter (clockwise, Fig. 1), thereby carrying 40 the ball which has previously entered onto the seat 42 from the runway 41 off the same and into the next adjacent ball exit opening 13, wherein it is temporarily retained until the sliding panel 14 is shifted (left to right, Fig. 2). This movement of the sliding panel 14 registers the exit 45 openings 45 therein with the exit openings 13 in the inclined playing board 12, whereupon the balls fall through the thus registered openings 13-45 upon the inclined ball return runway 46 by which they are returned to a point adjacent the propelling means (not shown).

After the indicator arm 39-40 has moved the first ball off the seat 42 into the adjacent ball exit opening 13, further movement of the member 39-40 will carry balls, one at a time, off the ball seat 42 past the ball or balls disposed in the circumferentially arranged row of exit openings 13, it being noted that to permit this movement of the balls the ball exit openings are arranged so that part of their peripheral surfaces project under the annular guide rail 52 (Fig. 1), so that a ball disposed between the arms 40 of the member 39 may travel past a ball disposed in one of the exit openings 13 but such a ball will overhang the marginal edges of the exit openings 13 and will drop into the next succeeding empty ball exit opening in the circumferentially arranged row of the same.

The indicator and ball-moving member 39-40 70 makes a complete revolution at each operation and is stopped in its initial position (as in full lines, Fig. 1) by the engagement of the latch pin 23-24 in the opening 25. As the ball is moved off the ball seat 42 the contacts 15-16 spread 75 apart under the action of their own resiliency

thereby opening the circuit 17, whereupon the resetting spring 22 acts upon the member 19 to pivot the latter (counterclockwise, Fig. 2), thereby opening the circuit 34 (Fig. 4), at 43, and at the same time engaging the upper end 5 portion 24 of the latch member 23 against the bottom of the pulley 26 so that when the opening 25 in the pulley 26 moves into registration with the pin 23 the spring 22 moves the upper end portion 24 of the pin 23 into the opening 10 25 which is provided in the pulley 26.

While I have illustrated and described the preferred form of construction for carrying my invention into effect, this is capable of variation and modification, without departing from the 15 spirit of the invention. I, therefore, do not wish to be limited to the precise details of construction set forth, but desire to avail myself of such variations and modifications as come within the 20 scope of the appended claims.

Having thus described my invention, what I claim as new and desire to protect by Letters Patent is:

1. In a game apparatus, the combination of: 25 a cabinet including a member providing a ball-playing surface provided with a ball seat; a member movably mounted in said cabinet and having a bifurcated portion normally positioned to engage a ball in said seat, said member being movable over said playing surface for moving balls 30 one at a time from said ball seat over said playing surface; and means including a device actuated by a spent or played ball for operating said second-named member.

2. In a game apparatus, the combination of: 35 a cabinet including a member providing a ball-playing surface having an annular row of ball-receiving pockets formed therein and provided with a ball seat arranged on the circumference of said annular row of pockets; a substantially 40 annular guide rail arranged upon said playing surface above and concentrically relative to said pockets and extending over and above a portion less than the entire area of each of said pockets; a member rotatably mounted in said cabinet 45 concentrically relative to said guide rail and pockets and having a bifurcated end portion positionable by movement of said second member to engage a ball on said seat and movable over said playing surface within said guide rail 50 so as to convey balls one at a time from said ball seat into said pockets; and means including a device actuated by a ball disposed upon 55 said ball seat for operating said second-named member.

3. In a game apparatus, the combination of: a cabinet including a member providing a ball-playing surface having an annular row of ball-receiving pockets formed therein and provided with a ball seat arranged on the circumference 60 of said annular row of pockets; a substantially annular guide rail arranged upon said playing surface concentrically relative to and above said pockets and extending over and above a portion less than the entire area of each of said pockets; a member rotatably mounted in said cabinet 65 concentrically relative to said guide rail and pockets and having a bifurcated end portion movable over said playing surface within said guide rail for positioning relative to said ball seat to engage a 70 ball therein so as to convey balls one at a time from said ball seat into said pockets when said second member is rotated; and means including a device actuated by a ball disposed upon said ball seat for operating said second-named mem- 75

ber whereby when a ball conveyed by the said bifurcated end portion of said member lodges in one of said pockets the same will underlie a portion of said guide rail so that subsequently 5 played balls may be conveyed one at a time by the said bifurcated end portion of said member past the said first-named ball and into the remaining pockets.

4. In a game apparatus, the combination of: a 10 cabinet including a member providing a ball-playing surface having an annular row of ball-receiving pockets formed therein and provided with a ball seat arranged on the circumference of said annular row of pockets; a substantially annular guide rail arranged upon said playing surface concentrically relative to and above said pockets and extending over and above a portion less than the entire area of each of said pockets; a member rotatably mounted in said cabinet concentrically relative to said guide rail and pockets and having a bifurcated end portion positionable by rotation of said member to receive a ball moving onto said seat and movable over said playing surface within said guide rail so as to 15 convey balls one at a time from said ball seat into said pockets; and means including a device actuated by a spent or played ball for operating said second-named member whereby when a ball conveyed by the said bifurcated end portion of said 20 member lodges in one of said pockets the same will underlie a portion of said guide rail so that

subsequently played balls may be conveyed one at a time by the said bifurcated end portion of said member past the said first-named ball and into the remaining pockets.

5. In a game apparatus, the combination of: a 5 cabinet including a member providing a ball playing surface provided with a ball seat; a member pivotally mounted upon said playing surface and movable thereover in a plane substantially parallel thereto into position to engage a ball moving onto said seat and for moving balls one at a time from said ball seat over said playing surface; and means including a device actuated by a ball entering onto said ball seat for operating said member; said member having a bifurcated end 10 15 portion for the reception of a ball disposed upon said ball seat.

6. In a game apparatus, the combination of: a cabinet including a member providing a ball playing surface provided with a ball seat; a member pivotally mounted upon said playing surface and movable thereover in a plane substantially parallel thereto for moving balls one at a time from said seat over said playing surface; and means including an electromagnetic device actuated by a ball entering onto said ball seat for operating said member; said member having a bifurcated end portion positionable by movement of said member for engagement of a ball disposed 20 25 upon said ball seat.

FRANK K. MAITLAND.
